UNITED STATES PATENT OFFICE.

RUTH LUCILLE GERTH, OF MINNEAPOLIS, MINNESOTA, ASSIGNOR TO ALFRED VESTER SONS, INC., OF PROVIDENCE, RHODE ISLAND, A CORPORATION OF RHODE ISLAND.

DESIGN FOR A PAN FOR LIGHTING FIXTURES.

Application filed March 27, 1922. Serial No. 1,407. Term of patent 14 years.

To all whom it may concern:

Be it known that I, RUTH LUCILLE GERTH, a citizen of the United States, and residing at Minneapolis, in the county of Hennepin and State of Minnesota, have invented a new, original, and ornamental Design for Pan for Lighting Fixtures, of which the following is a specification, reference being had to the accompanying drawing, forming part thereof.

Fig. 1 is a plan view of a pan for lighting fixtures showing my new design;

Fig. 2 is a side view of the same.

I claim—

The ornamental design for a pan for lighting fixtures, as shown.

RUTH LUCILLE GERTH.
